UNITED STATES PATENT OFFICE

155,878

DESIGN FOR A VEHICLE

Roy F. Dibble, Milwaukee, Wis.

Application May 9, 1947, Serial No. 138,957

Term of patent 14 years

(Cl. D14—3)

To all whom it may concern:

Be it known that I, Roy F. Dibble, a citizen of the United States, residing at Milwaukee, in the county of Milwaukee and State of Wisconsin, have invented a new, original, and ornamental Design for a Vehicle, of which the following is a specification, reference being had to the accompanying drawing, forming a part thereof.

Figure 1 is a side view of the vehicle.

Figure 2 is a reverse side view of the vehicle.

Figure 3 is a front view of the vehicle.

Figure 4 is a rear view of the vehicle, and

Figure 5 is a top plan view of the vehicle on a reduced scale.

The characteristic features of my design reside in the portions shown by means of full lines in the drawing.

I claim:

The ornamental design for a vehicle, as shown and described.

ROY F. DIBBLE.
